UNITED STATES PATENT OFFICE

2,667,400

APPLIANCE OF THE DRAWER TYPE

Gaylord H. Wotring, Fairfield, Conn., assignor
to General Electric Company, a corporation of
New York

Application May 9, 1952, Serial No. 286,871

1 Claim. (Cl. 312—331)

1

This invention relates to drawer-type appliances, such as under-the-counter dishwashers, clothes-washers, cabinets, and the like.

Under-the-counter appliances heretofore have been provided with extensible-retractable slides of the type such as are used in office cabinet drawers and the like. These slides, while quite satisfactory as to operation, are rather costly in that they comprise several metallic slides and associated ball bearing rollers engageable with the slides.

This invention has for its principal object the provision of an improved, simplified slide arrangement for the appliance, arranged to support it in its retracted position; to support it as it is moved between its retracted and withdrawn positions; to facilitate the movement of the appliance back and forth between its retracted and withdrawn positions; and to reduce the cost of the slide.

Briefly stated, in accordance with one aspect of my invention, I eliminate the relatively complicated and expensive extensible retractable slide structures of the rail type heretofore used. I utilize a pair of simple, spaced-apart and fixed supporting rails on which a pair of wheels mounted on an end portion of the appliance rim so as to support that portion of the appliance, and to provide for the movement of the appliance as a whole to its withdrawn and retracted positions. The appliance is balanced about the 30 wheels by a cable arrangement operating over suitably arranged and positioned pulleys, and interconnecting the appliance and its cabinet or counter structure so as to support the appliance in a horizontal position throughout its range of movement into and out of the cabinet. Also in certain embodiments of this invention, means are provided in the organization providing for lateral stability. In one embodiment of the invention, the cable structure is arranged to accomplish this function. In another, this function is accomplished by interconnected gear wheels on the appliance coacting with stationary racks.

My invention will be better understood from the following description taken in connection 45 with the accompanying drawings and its scope will be pointed out in the appended claim.

In the drawings, Fig. 1 is a side elevation of an appliance of the drawer type embodying this invention showing the appliance in its withdrawn position, and having parts broken away and parts shown in section to illustrate certain details of construction; Fig. 2 is a view similar to Fig. 1 but illustrating the appliance in its withdrawn position; Fig. 3 is a perspective view illustrating the 55 appliance with its cabinet substantially removed;

2

Fig. 4 is a perspective view illustrating a portion of an appliance and associated slide mechanism therefor arranged in accordance with a modified form of this invention; Fig. 5 is a view similar to Fig. 1 but illustrating still another form of this invention, and showing the appliance in its retracted position; and Fig. 6 is a view similar to Fig. 5 but illustrating the appliance in its withdrawn position.

Referring to the drawings, this invention has been shown as applied to an appliance such as an under-the-counter dishwasher of the type described and claimed in the copending application of Jacob W. McNairy, Serial No. 228,465, filed 15 March 26, 1951, and assigned to the General Electric Company, the assignee of the instant application. The dishwasher 1 is mounted under a horizontal table-like work surface such as a counter 2, which is the top wall or surface of a suitable cabinet. The cabinet rests on a base formed by horizontal channels 3, and at the top the cabinet is provided with horizontal frame channels 4; channels 3 and 4 are suitably interconnected by vertical frame members (not shown) to form a box-like framework. It will be understood that the cabinet will be closed at the sides and rear with suitable panels (not shown) attached to the frame channels. At the front, however, is a panel 5 having an opening 6 therein which constitutes the front opening of the cabinet and through which the dishwasher 1 may be withdrawn. The front panel 5, together with the base, is arranged to provide a toe space 7 at the bottom; and over the toe space is a transverse frame channel 8. The specific details of construction of the cabinet do not constitute a part of this invention and it is believed, therefore, to be unnecessary to describe the cabinet in greater detail.

The dishwasher 1 comprises a tub 9 substantially square in horizontal cross section, formed of walls which are open at the top to define a top opening which lies in a plane substantially parallel with the top counter surface, and to which access is had to the tub for the insertion and removal of dishes and utensils to be cleaned. The tub is supported by suitable means in accordance with this invention so that it may be withdrawn from the cabinet like a drawer from the position of Fig. 1 to the position of Fig. 2, so that the dishes and utensils may be loaded into the tub for the washing operation which is effected when the tub is moved back to its withdrawn or retracted position shown in Fig. 1. When the tub is in its retracted position, it is closed by means of a suitable closure member 10 operated

by a handle 11 accessible at the front of the cabinet in the manner described and claimed in the aforementioned McNairy application. The front of the tub carries a front panel 12 which closes the front opening 6 of the cabinet when the tub is pushed back into it. It will be understood that the tub will carry within it suitable trays (not shown) for supporting the utensils to be cleaned, and with a suitable impeller (also not shown) for circulating water over and about the dishes to wash them; the impeller is provided with an exterior driving motor 13 located below the tub and carried by it.

The means for mounting the dishwashing machine 1 for sliding movement between its retracted position of Fig. 1 to its extended position of Fig. 2 and for movement back to its position of Fig. 1, in accordance with this invention, comprises a pair of fixed rails 14 located in the bottom of the cabinet on the base frame channels 3 so as to be supported by them, and at the sides of the cabinet and directed in parallel relation with respect to each other and the direction of movement of the machine 1 into and out of the cabinet. Mounted on the lower rear side portions of the machine 1 are a pair of wheels or rollers 15 which coat with the two rails 14, so as to support the machine 1 for sliding movement on the rails; the rails are provided with upright guiding flanges 14a (Fig. 3) for the wheels. Preferably and as shown, the rollers 15 will be mounted on rearwardly extending sections 16 on the machine 1 so that when the machine is moved into the forward part of the cabinet for withdrawal, it will be substantially completely removed from the cabinet, as clearly shown in Fig. 2, and preferably the two wheels or rollers 15 will be mounted upon a common transverse shaft 17 journaled in the extensions 16, as clearly shown in Fig. 3.

Coacting with the rollers 15 to support the appliance 1 are a pair of non-extensible cables 18 at the opposite side portions of the appliance; these cables may be made of any suitable material such as a flexible steel, and they may be of any suitable form as a tape, or as a rope cable as shown in Figs 1 to 3. The upper end of each cable 18 is anchored to a pin 19 fixed to the upper frame member 4 at the rear of the cabinet. From this anchor, each cable is directed over a pulley 20 journaled to the tub 9 at the upper rear side wall thereof. The two pulleys 20 for the two cables preferably will be mounted upon and fixed to a common transverse shaft 21 which will be journaled in a pair of ears 21' fastened to the upper rear wall portion of the tub 9. From these pulleys 20, the two cables 18 are directed downwardly at the rear of the tub 9 to pass over pulleys 22 mounted upon the transverse shaft 17. The pulleys 22 are not fastened to the shaft 17 to rotate it, but are freely rotatable thereon with respect to it. From the pulleys 22, the cables are directed forwardly under the appliance 1 to the forward part thereof, where the other ends of the cables are anchored to the transverse frame member 8 by means of L-shaped bolts 23, one leg of which is directed through an eye 24 attached to each of these other ends of the cables, as shown. The other legs of the L-shaped bolts 23 are mounted in upright ears 25 provided on the frame 8, and the bolts are secured by means of a pair of nuts 26, which function not only to secure the bolts but also to adjust the tensions in the two cables 18.

It will be observed that by reason of the cables

operating on the pulleys 20 and 22 and having their ends anchored as described, they interconnect the appliance and cabinet so as to function to support the appliance 1 about the rollers 15 as a fulcrum. That is, the two cables function to support the appliance 1 in an upright position within the cabinet, and they also function to support the appliance within this position as it is moved from its retracted to its withdrawn position, and vice versa. More specifically, the two pulleys divide the non-extensible cables into three portions 18a, 18b, and 18c. When the appliance 1 is withdrawn from the cabinet, the portion 18a increases in length as the portion 18c correspondingly decreases in length, the portion 18b of course retaining a substantially constant length throughout. In this way, as the appliance 1 is moved between its retracted and withdrawn positions, it is constantly maintained in a vertical position throughout. Conversely, when it is moved back into the cabinet, the length 18a decreases as the length 18c correspondingly increases, and here again the appliance 1 is maintained in its vertical position throughout.

Some degree of lateral stability may be obtained by keying the top and bottom pulleys to rotate with their respective common shafts.

In order to insure absolute lateral stability, the cables may be arranged as shown in the form of this invention illustrated in Fig. 4, where all of the elements have substantially identically the same construction as the corresponding elements shown in Figs. 1 to 3, except that the cables at the rear are reversed. As here shown, the two cables 27 have their lengths or portions 27a and 27c arranged as are the corresponding portions 18a and 18c of the cables 18, but here the vertical portions 27b instead of being arranged vertically at the same side of the appliance as are their parts 27a and 27c, are crossed over at the rear, so that the left-hand cable at the bottom becomes the right-hand cable at the top, and so that the right-hand cable at the bottom becomes the left-hand cable at the top. This arrangement provides for absolute lateral stability of the appliance 1 as it is moved in and out of its cabinet.

In another form of this invention illustrated in Figs. 5 and 6, the positions of the anchors and of the pulleys are reversed in the sense that the anchors are fixed to the appliance, whereas the pulleys are fixed to the cabinet. Thus, in this form of the invention, a cable 28 is provided at each side of the appliance 1, but it has its upper and lower ends anchored respectively to the upper and lower portions of the tub 9; thus, the upper end of the cable is attached to an adjustable anchor 29 provided on the upper side wall of the tub adjacent its rear end, whereas the other end of the cable is provided with a fixed anchor 30 attached to the lower rear corner of the tub. Each cable 28 is directed from the upper anchor 29 to a pulley 31 rotatably mounted on the cabinet at its upper rear end, thence is directed forwardly to pass over a pulley 32 fixed to the lower forward corner of the cabinet, and from this pulley is directed backwardly to its anchor 30. Here the cables function precisely in the same fashion as do the cables 18 of the first form of the invention described, i. e., as the appliance 1 is moved from its retracted to its withdrawn positions, the portions 28a of the cables increase in length as the portions 28c of the cables correspondingly decrease in length, the portions 28b throughout remaining substantially constant in length. And here again, the

two cables support the appliance 1 in its vertical position throughout its movement in and out of the cabinet. They do not, however, effectively stabilize the appliance laterally as do the two cables 27 of the form of the invention shown in Fig. 4. This may be accomplished in the form of the invention shown in Figs. 5 and 6 by means of a pair of gear wheels 33 fixed to the pulleys 31 and meshing loosely with a toothed track 34 at each side of the appliance. In other words, the members 31 may be a combination roller and gear wheel riding on and meshing with a track 32, or these two elements may be separate in the sense that the roller may operate on a smooth rail and the gear member operate in a separate rack.

While I have disclosed particular embodiments of my invention, it will be understood, of course, that I do not wish to be limited thereto, since many modifications may be made, and I, therefore, contemplate by the appended claim to cover any such modifications as fall within the true spirit and scope of my invention.

What I claim as new and desire to secure by Letters Patent of the United States is:

In an appliance structure having walls defining a fixed cabinet having a front opening therein and an appliance in said cabinet, slide means for said appliance comprising a pair of spaced apart rails in the lower portion of said cabinet

30

lying in a direction normal to said front opening, a pair of wheels on the sides of and toward the rear of said appliance rolling on said rails respectively to movably support said appliance at the rear, a pair of fixed anchors at the upper rear of said cabinet spaced apart transversely thereof and a pair of fixed anchors at the lower front of said cabinet spaced apart transversely thereof, two pairs of transversely spaced pulleys on said appliance at the upper and lower rear portions thereof respectively, a pair of non-extensible cables, each anchored at one end to the anchor means on one side of said cabinet at the lower front thereof and directed back therefrom to pass over the pulley at the lower portion of the appliance at that side and thence directed upwardly and laterally of said appliance to pass over the pulley at the upper rear thereof on the other side of the appliance and from which it is directed to said anchor at said other side at the top of said cabinet and means for attaching it to said anchor, thereby to provide lateral stability of said appliance.

GAYLORD H. WOTRING.
